UNITED STATES PATENT OFFICE.

JOHANNES DIEM-BEUTLER, OF BRUGGEN, NEAR ST. GALLEN, SWITZERLAND.

METHOD OF PRODUCING A CHAIN-STITCH.

No. 917,420.

Specification of Letters Patent.

Patented April 6, 1909.

Application filed August 19, 1907. Serial No. 389,237.

To all whom it may concern:

Be it known that I, JOHANNES DIEM-BEUTLER, a citizen of Switzerland, and resident of Bruggen, near St. Gallen, Switzerland, have invented a new and useful Method 5 of Producing a Chain-Stitch, of which the following is a specification.

My invention relates to such a method of producing chain-strokes similar, or nearly 10 similar, on both sides of the material. This stitch is to be used principally for the embroidery of curtains or similar tissues, which are desired to be alike on both sides.

My method is illustrated step by step in 15 Figures 1-8 of the accompanying drawings, but the implements used are only shown diagrammatically. Figs. 1, 3, 5 and 7 show the stitch in the longitudinal direction of the seam and Figs. 2, 4, 6 and 8 show the corresponding positions in the transverse direction of the seam.

For carrying out my method I use a bobbin 20 a turning on a vertical axis and consisting of a cylindrical box with an opening a' provided eccentrically at the upper edge for letting out the thread. In the direction of the axis of the bobbin a there moves up and down, above 25 the same, a hooked needle c. In the transverse direction moves horizontally a tongued-needle e above the center of the bobbin a to and fro, whose hook is provided with a closing tongue e'. Close above the needle e is a 30 needle-plate f of the usual kind which serves as a support to the material d to be embroidered.

When a stitch is to be made the thread b coming out of the bobbin a (Figs. 1 and 2) is drawn with the hooked-needle c through the material d. The tongued-needle e has passed 35 through the loop previously formed by it (Fig. 2) toward the left. Now the material d on the needle-plate f is advanced by the length of a stitch. The hooked-needle c passes through the material downward (Figs. 40 45 3 and 4) and holds fast with its shank the

loop g of the thread b after the same has been drawn up. The thread b passing from the bobbin, in consequence of the rotation of the same, below the tongued-needle e, is, at the same time seized by the latter and drawn 50 back (Fig. 4) toward the right. By the further rotation of the bobbin a the thread b is now put into the hook of the lowered needle c (Figs. 5 and 6) and the latter commences to move upward again, while the tongued-needle e continues in its movement (Fig. 6) toward the right, so that the thread seized by it is drawn along by it and the loop previously formed by it, and now lying on it, is 55 brushed off from it by this movement. Now 60 the needle c moves further upward as far as possible (Figs. 7 and 8) and draws in this way the thread through the material, while the tongued-needle draws the loop previously seized by it likewise entirely through 65 the loop slipped off from it. The material d lying on the needle plate f is now moved forward again by the length of a stitch and the process is repeated.

Having now described my invention what 70 I claim and desire to protect by Letters Patent is:

A method of producing by means of one thread a stitch having at both sides of the material a form like a well known chain 75 stitch, consisting in drawing the thread from one side through the material thereby forming a loop at the other side of the material, leaving at the same time a loop at the side from which the thread is drawn through the 80 material, keeping both loops in position by suitable means, transporting the material the length of a stitch, and drawing again the thread through both loops and the material.

In witness whereof I have hereunto set my 85 hand in the presence of two witnesses.

JOHANNES DIEM-BEUTLER.
